UNITED STATES PATENT OFFICE

DARIUS E. SHRAUGER, OF ATLANTIC, IOWA

WINDOW-SCREEN CONSTRUCTION

Application filed September 24, 1928. Serial No. 307,841.

The object of my invention is to provide a window screen construction of simple, durable, and comparatively inexpensive construction.

Another and most important object of my invention is to provide a screen construction wherein the screen frame and the mounting means therefor are made of metal, wood, or other suitable material, the screen frames being easily and conveniently removable from the inside of the building to which the screen is applied and equally as well adapted to be replaced.

Still a further object is to provide a screen construction consisting of mounting bars to be permanently attached to a window frame and a pair of screen units adapted to be mounted thereon, which may be easily removed through the lower half of the window opening after the inner sash has been raised.

Still another object is to provide a screen construction so constructed as to compensate for expansion and contraction so that a good fit and one which is fly-tight results at all times.

Still a further object is to provide in connection with one of the screen units a movable cover plate which may be raised for the purpose of sweeping dust and the like from the window sill where it has accumulated.

More particularly, it is my object to provide in connection with the supporting bars, a friction means for holding one of the screen units after it has been inserted and raised to position and latching means for holding the other screen unit in position after it has been placed against the supporting bars.

Still a further object is to provide my construction easily adapted to be covered by window glass for the purpose of forming storm sashes, whereby for each window, screen units and storm sash units may be provided so that the owner may change from one to the other each fall and spring.

With these and other objects in view my invention consists in the construction, arrangement and combination of the various parts of my device, whereby the objects contemplated are attained, as hereinafter more fully set forth, pointed out in my claims, and

illustrated in the accompanying drawings, in which:

Figure 1 is a perspective view of my window screen construction showing it applied to a window frame and viewed from the outside of the frame. 55

Figure 2 is a vertical sectional view of the same on the line 2—2 of Figure 1.

Figure 3 is a perspective view of parts of the screen frame shown in disassembled position and illustrating how the edge of the screen wire is secured to the screen frame. 60

Figure 4 is an elevation of my device as viewed on the line 4—4 of Figure 2, and showing the window frame in section. 65

Figure 5 is an enlarged horizontal sectional view on the line 5—5 of Figure 4.

Figure 6 is a perspective detail view of a corner of the screen frame, illustrating the manner in which it is assembled. 70

Figure 7 is an elevation of the same corner, showing it after it has been assembled and welded together.

Figure 8 is an enlarged sectional view on the line 8—8 of Figure 4, illustrating the 75 manner in which an edge of the screen wire is held in the screen frame; and

Figure 9 is a similar sectional view omitting the screen and showing a pane of glass, whereby a storm window may be made. 80

On the accompanying drawings, I have used the reference numeral 10 to indicate the sill of an ordinary double sash window frame. The window frame also includes side casings 12, a head casing 14, side blind stops 16, which are ordinarily embedded in side jambs 18 and a head blind stop 20 ordinarily embedded in a head jamb 22. 85

The foregoing description is of the ordinary type of window to which I apply my window screen construction and forms no part of my invention. 90

My window frame construction consists of a pair of spacer and supporting bars A and a removable frame covered with screen wire and consisting of two parts; an upper unit B and a lower unit C. Each supporting bar A consists of a flange 24 adapted to be fastened by means of screws 26 to the side jambs 18 of the window frame. 95

Portions 28 are formed on the bars A which extend toward each other, as clearly illustrated in Figure 5 of the drawings. The portions 28 terminate in inwardly opening channels 30. The channels 30 it will be noted, are closer together than the facing surfaces of the side blind stops 16 for a purpose which will hereinafter be more fully set forth. The portions 28 in this connection, 10 serve the purpose of spacing the channels 30 from the side jambs 18.

The supporting bars A are made of the proper length to fit between the head jamb 22 and the sill 10 of the window frame. The 15 lower ends of the bars A of course, are cut at an angle to fit the sill, as shown in Figure 2.

Means are provided on the supporting bars A to hold the screen units B and C in position and these means consist of friction plates 32 and latches 34. The friction plates 32 have flanges 36 which are held in position against the flanges 24 of the supporting bars A by means of some of the screws 26, as 25 clearly shown in Figure 5.

The lower ends of the friction plates 32 are bent slightly away from the supporting bars A, as indicated at 38. The latches 34 are pivoted to the supporting bars A by 30 means of rivets or the like 40.

The screen units B and C each consists of a frame covered with screen wire. The frame of the unit B comprises side members 42 and top and bottom members 44 and 46. The 35 frame of the unit C comprises side members 48 and top and bottom members 50 and 52. Each of the members 42, 44, 46, 48, 50 and 52 is formed in the same die and consists of a flange portion 54, an inwardly opening 40 channel portion 56, and an outwardly opening channel portion 58.

Referring to Figure 6 of the drawings, the ends of the members 44, 46, 50 and 52 are connected with the members 42 and 48, as 45 illustrated. Referring for instance, to the upper left hand corner of the unit B shown in Figure 1, the member 42 is cut away as indicated at 60 to receive the outwardly opening channel portion 56 of the member 44.

The channel portion 56 is formed with a 50 lip 62 adapted to rest against the bottom of the channel portion 56 of the member 42. When these two parts are assembled together by moving the member 44 as indicated by 55 the arrows, they appear as shown in Figure 7 and are rigidly held assembled relative to each other by spot welding at the points referred to by the reference numeral 64.

After the frames of the units B and C have been assembled, the screen covering 66 for each of the frames is put on in the following described manner. The covering 66 is cut slightly larger than the outside dimensions of the screen frame and is laid 60 against the inside surface thereof. In each

of the inwardly opening channels of the screen frame, a filler member 68 (see Figure 3) is inserted into the inwardly opening channel of each of the four frame members of each screen unit.

The screen originally assumes the position shown in dotted lines and as the channel-shaped filler member 68 is pressed into the inwardly opening channel 56 of the screen frame the screen 66 assumes the position shown in full lines as it enters the channel. For each screen frame of each unit, four of the filler members 68 are provided. The 75 filler members 68 are formed of sheet metal so that after being forced into the inwardly opening channels 56 they may be pierced by case hardened screws 70 which form therein, threads in the members 68 as they enter them.

Openings 72 are provided in the bottoms 85 of the channels 56 for receiving the screws 70. Besides causing a tight engagement between the screen frame and the screen 66, the filler members 68 serve to stretch the wire 66 tightly over the screen frame.

The side members 48 of the screen unit C extend considerably lower than the bottom member 52 thereof. Thus, a space is left between the screen wire 66 and the lower end of the frame of the unit C. This space is 90 provided for the purpose of sweeping dust and dirt from the window sill and outdoors.

A cover plate 74 is provided to span the distance between the bottom member 52 and the window sill 10. The plate 74 is provided with a pair of slotted openings 76 through which rivets 78 extend. The rivets 78 are secured to the flanges 54 of the side members 48. By means of the slotted openings 76 the cover plate 74 may be raised and then swung slightly to the right, as viewed in Figure 4, so that the portions 80 of the slots 76 coact with the rivets 78, whereby the cover plate may be held in raised position. 100 A strip of metal is secured to the upper end of the frame of the screen unit C for forming a flange 82 to contact with the upper screen unit B.

Installation and practical operation of my screen structure

In the installation of my device the flanges 24 of the supporting bars A are positioned against the side jambs 18 of the window frame, as shown in Figure 5. The inner edges of the flanges 24 are caused to contact with the side blind stops 16, whereby they serve to position the supporting bars A for aligning the channels 30 thereof with the outer surfaces of the side casings 12. The screws 26 are then utilized for the purpose of permanently securing the supporting bars A to the window frame.

The upper screen unit B may now be placed 130

in the position of the lower screen unit with the flanges of the outwardly opening channels thereof which are at the extreme side edges of the screen unit B positioned in the inwardly opening channels 30 of the supporting bars A. The screen unit B may now be pushed upwardly. The side members 42 thereof in being so pushed, will enter under the lip portions 38 of the friction plates 32 and when the screen unit B is in its uppermost position, as shown in Figure 2, the plates 32 will serve to hold it in such position.

A filler 84 formed of wood or sheet metal may be nailed to the head jamb 22 for the purpose of filling the space between the upper screen unit B and the head blind stop 20. The lower screen unit C may now be placed with the lower end thereof on the sill 10 as shown in the dotted line position in Figure 2. The upper end thereof is then caused to swing inwardly as indicated by the arrow 86 (the latch members 34 being in raised position as shown at the left hand side of Figure 4). The flange 82 will then contact with the upper screen unit B for closing the joint between the two units.

The latches 34 may now be swung downwardly, as indicated at the right hand side of Figure 4 and in dotted lines at the left hand side thereof. The inwardly opening channel 30 of the supporting bar A and the outwardly opening channel 58 of a side bar of one of the screen frames coact with each other, as shown in Figure 5. By such coaction, ample space is left to allow for contraction and expansion of the screen frames or the window frame.

The inwardly opening channels of the supporting bars A are spaced closer together than the distance between the side blind stops 16 and the dimensions of the screen units B and C from side to side thereof are such that they can fit into the channels 30.

The over-all width therefore, of the screen units B and C is less than the distance between the blind stops 16, whereby the screen units may be removed from the supporting bars A from the inside of the building. This is one of the main advantages of my construction.

In the event that the device is to be used for a storm sash in the winter time, frames may be provided similar to the frames for the screen 66, but omitting the screen, the filler channels 68, and the screws 70.

The flanges 54 of the frame members may be faced with putty, as indicated at 88 in Figure 9. A pane of glass 90 is then placed against the putty and held in position by metal clips 92. The clips 92 are fastened to the inwardly opening channels 56 of the frame members by means of screws or bolts 94.

My construction works very satisfactorily

as a storm sash, since the entrance of air is eliminated by the double joint construction consisting of the outwardly opening channels of the unit frames and the inwardly opening channels of the supporting bars A 70 coacting with each other, as shown in Figure 5. The filler 84 prevents the entrance of air at the top of the storm sash, the flange 82 prevents the entrance of air at the center of the storm sash, and the cover plate 74 prevents the entrance of air below the storm sash.

The cover plate 74 may be brought to raised position for the purpose of allowing ventilation through the storm sash. 80

From the foregoing construction as described in my specification it will be obvious that I have provided a window screen or storm sash construction in which the upper and lower units of the device may both be 85 easily and conveniently removed or replaced with respect to the supporting bars A and by only raising the inner sash of the window.

Making the screen or storm sash frame in two parts allows for the units being removed through the opening left by the inner sash of the window being raised. 90

Some changes may be made in the construction and arrangement of the parts of my device without departing from the real spirit 95 and purpose of my invention, and it is my intention to cover by my claims, any modified forms of structure or use of mechanical equivalents, which may be reasonably included within their scope. 100

I claim as my invention:

1. For use with a window frame having a window therein, a device of the class described comprising a supporting bar adapted to be secured to a side of said window frame and having an inwardly opening, longitudinally arranged channel, and a removable frame associated with said bar and having a frame member provided with an outwardly opening channel, a flange of said outwardly opening channel being received in said inwardly opening channel. 105

2. A device of the class described comprising a supporting bar adapted to be secured to a side of a window frame in spaced relation to window sash therein, a removable frame having a frame member associated with said bar, said removable frame being formed in two parts, means on the supporting bar to slidably receive one of said parts, 110 the spacing of said bar from the sash permitting the insertion and removal of said frame from within when one sash is open, and means to retain the other part independent of the window sash of the window frame 115 against said bar.

3. For use with a window frame having a window opening therein and a blind stop projecting toward the center of said window opening, a device of the class described com- 120

125

prising a supporting bar secured to a side of said window frame outside of said blind stop and spaced from sash in the window opening, said bar having an inwardly opening, longitudinally arranged channel, and a removable frame, having its outer edge closer to the center of said window frame than the inner surface of said blind stop, said removable frame being associated with said bar and having an outwardly opening channel, a flange of said outwardly opening channel being received in said inwardly opening channel.

4. For use with a window frame having a window opening therein, of a supporting member adapted to be permanently secured to the window frame and a screen having a frame member removably associated with said supporting member, one of said members being channel shaped and the other one having a flange received in such channel shaped member, by insertion of the flange into the channel and means behind the flange for locking the flange in the channel.

5. For use with a window frame having a window opening therein, and a window sash covering said opening, a supporting bar adapted to be permanently secured to the window frame and a screen removably associated with said bar, said screen being formed in two units, means for frictionally holding one unit relative to the supporting bar, both of the units being spaced from said window sash.

6. A structure adapted for use with a window frame, having blind stops, and a sash in the frame, including spacer and supporting means provided with members for attaching them to the window frame, said members being concealed between the supporting means and the blind stops, a removable frame detachably associated with said supporting means, and securing elements for fastening the frame to the supporting means, in position spaced from the sash.

7. A screen structure comprising a supporting bar having a longitudinally extending channel in one face, a removable frame adapted to be associated with said bar, said frame including a frame member formed with a longitudinally extending channel arranged oppositely to and adapted to inter-engage and coact with the channel of said bar, and means for detachably holding said frame member in engagement with said bar.

8. A screen structure comprising a supporting bar formed with a longitudinally extending channel near one of its margins, a frame adapted to be removably associated with said bar, said frame including a frame member formed with an angular, longitudinally extending projection near one of its margins, said projection being of less width than the channel of said bar and being received therein to provide a laterally adjust-

able inter-engaging joint between the frame and the bar, and means for engaging said frame on the side opposite to said projection for holding it in engagement with said bar.

Des Moines, Iowa, September 18, 1928.
